FLEXIBLE WAVE GUIDE

Robert S. Carr, Maplewood, N. J., assignor to Airtron, Inc., Linden, N. J., a corporation of New Jersey

Application May 11, 1949, Serial No. 92,640

6 Claims. (Cl. 138—56)

This invention relates to improvements in flexible waveguides and more particularly to waveguides which are suitable for being subjected internally to fluid pressure and to contain such pressure to enhance the conduction characteristics of the waveguide.

Waveguides, as referred to herein, are ordinarily employed for the purpose of transmitting micro-waves in radar and television equipment and in other equipment in which electrical impulses, usually of high frequency, are present and require conduction between various components of the apparatus. Under many conditions it is necessary or desirable to provide waveguides which are flexible, to permit limited movement or vibration of various parts of such apparatus relatively to each other or to permit contortion of the waveguide to facilitate its installation in the apparatus.

It has been found that waveguides should preferably be hollow and rectangular in cross section, and to meet these requirements while nevertheless providing for flexibility in the waveguide, it has become more or less conventional practice to form the guiding or conducting portion of the waveguide of hollow, thin metal tubing of rectangular cross section having peripherally extending corrugations to impart flexibility to the tubing. Such flexible tubing can be produced in various ways as, for example, by merely pressing such corrugations into a previously formed more or less rigid tubing or by winding a longitudinally convoluted strip of thin, flexible metal spirally upon a rectangular mandrel in such a way that the convolutions of each turn of the strip about the mandrel interlock with each preceding and succeeding turn, thereby forming a continuous tube. In forming the guiding or conducting core of the waveguide in the latter manner, it is desirable to solder the spiral seam so that there is no air leakage through or slippage in said seam; the flexibility of the metal in the convolutions being relied upon to give the requisite flexibility to the hollow, tubular core. Sometimes the solder is omitted from the seam so that a certain amount of slippage is present therein. While this may enhance the flexibility of the waveguide to some extent, it has been found that it does not yield best results from the standpoint of micro-wave guidance or conduction.

A complete waveguide includes suitable connecting flanges or equivalent connecting means fixed to the opposite ends of a length of such a hollow, metal, tubular core and commonly is provided with an outer jacket of rubber, synthetic rubber or other rubber-like material.

It has been found that waveguides are much more efficient for micro-wave guiding and conduction purposes, if the waveguides and other parts of a wave conduction system are maintained with fluid pressure therein substantially greater than atmospheric pressure. The present invention comprehends improvements in flexible waveguides which enable them to contain a fluid such as air under pressure, thereby rendering them suitable for use in such pressurized systems.

It is an important object of the present invention to provide waveguides which are adequately flexible but which nevertheless have the capacity of containing air under substantial pressure without material leakage.

Another important object of this invention is the provision of a flexible waveguide in which connecting flanges at one or both ends thereof are adapted for firm affixation to the metal conducting core of the waveguide and are grooved peripherally to afford a fluid-tight interlock with a rubber-like jacket which covers the said core.

Another important object is the provision, in a flexible waveguide, of means for preventing material out-

2

ward distortion or bulging of the metal conducting core as a result of substantial air pressure therewithin, while nevertheless preserving substantial flexibility in the core.

Another object of this invention is the provision of a flexible waveguide having means for preventing material outward distortion or bulging of the metal conducting core in the presence of substantial pressure therewithin and having connecting flanges or their equivalent firmly and fluid-tightly fixed at opposite ends of the said core, and improved means affording an interlocking, fluid-tight connection between such flanges and a rubber-like jacket provided as a covering for the core.

The foregoing and other objects of this invention should be apparent from the following description and the accompanying drawing in which:

Fig. 1 is a side elevational view, partly in central axial section, of a flexible waveguide according to the present invention;

Fig. 2 is a cross-sectional view at one flanged end of the said waveguide, the section being substantially on the line 2—2 of Fig. 1;

Fig. 3 is a cross-sectional view at one flanged end of the said waveguide, the section being substantially on the line 3—3 of Fig. 1;

Fig. 4 is a view toward one end of a modified form of waveguide according to this invention, the said view being partly in side elevation and partly in central axial section, and being broken away in layers to show certain interior parts in side elevation;

Fig. 5 is a view substantially like the left side of Fig. 1, showing a further modified form of flexible waveguide according to this invention; and

Fig. 6 is a view substantially like Fig. 4 but showing a still further modification within the present invention. Referring to Figs. 1—3, inclusive, the flexible waveguide illustrated therein comprises a flexible, metal, tubular core 11, which is rectangular in cross section and is shown as having plural peripheral corrugations or convolutions 12 suitable for imparting flexibility to said core. As the particular conformation of the convolutions and the manner of forming them do not form any essential part of this invention, such convolutions are shown in the drawing only diagrammatically rather than in detail. Although it is considered preferable that the metal, tubular core be convoluted, nevertheless it should be understood that the present invention also comprehends flexible waveguides which may have other structural provisions for yielding flexibility as, for example, an unsoldered slip joint or seam between turns of interlocking, non-convoluted strip metal.

Connection elements in the form of connecting flanges 13 preferably are fluid-tightly fixed upon the core 11 at the ends of the latter as by soldering at 14, to afford means for connecting the waveguides to other pieces of equipment; and a jacket 15 of relatively soft rubber, synthetic rubber or other rubber-like flexible material is suitably molded in place to completely surround the portion of the core between the said connecting flanges. The jacket 15 conforms in outer shape to the core 12, having a wall of substantially uniform thickness except as noted hereafter.

The connecting flanges 13, as illustrated, have a main or body portion 16 with bolt holes 17 therein to receive bolts for inter-connecting the waveguide between other pieces of equipment. Although similar flanges are illustrated at opposite ends of the waveguide, it is, of course, within the present invention to provide different flanges or equivalent connecting means at opposite ends of the waveguide, and means other than bolts may be employed to effect connection with other pieces of equipment. For this reason such connecting flanges or other suitable means for inter-connecting the waveguide with other equipment are sometimes referred to herein and in the claims as "connection elements."

As best seen in Fig. 1, the connection element 13 has an interlocking portion 18, integral with the body portion 16, and extending therefrom in a generally longitudinal or axial direction. The interlocking portion 18 is formed with a continuous inner peripheral groove 19 adjacent to the body portion 16, and a continuous outer peripheral groove 20 toward the free end of said interlocking portion.

The provision of the mentioned grooves gives the interlocking portion 18 a somewhat zigzag or convoluted shape as viewed in axial section as it appears in Fig. 1. The interlocking portion thus consists of an outer longitudinally extending web 21, a transverse or radial web 22 which connects the web 21 to an inner longitudinally extending web 23, and a transverse or radial flange 24 which extends outwardly from the web 23.

It may be observed that the inner diameters of the web 23 are greater than the corresponding outer diameters of the flexible metal core 11, so that when the jacket 15 is molded to constitute part of the device, the rubber-like material of that jacket extends between the web 23 and the core 11 and extends into and completely fills the inner peripheral groove 19. Also, it may be observed that the outer diameters of the radial flanges 24 are less than the corresponding outer diameters of the web 21, so that when the jacket 15 is molded in place, the rubber-like material thereof completely encases the flange 24 and extends into and completely fills the outer peripheral groove 20. Under the last mentioned conditions the rubber-like material of the jacket may be formed to give it outer diameters at the connection element which are the same as the corresponding outer diameters of the web 21, so that the adjacent outer surfaces of the said web and of the jacket are in effect continuous uninterrupted surfaces; the rubber-like material of the jacket being smoothly graduated from the connection element into the main body portion of the jacket without any undesirable lumps or ridges.

It may be seen that under the above described arrangement there exists a firm mechanical and fluid-tight interlock between the jacket 15 and the connection element 13. It should be appreciated that, although the flexible metal core may be made to be air-tight, it may nevertheless develop slight leaks which would enable fluid pressure to escape from within the core. If this occurs and if the pressure within the waveguide is not extremely high, the jacket 15 should prevent the escape of air and thus maintain the pressure within the waveguide. In this condition, however, the described interlocking arrangement between the jacket 15 and the connection elements 13 is of considerable importance; for without it, air leaking from within the core 11 would pass longitudinally between the latter and the jacket 15 and would eventually find avenues of escape at the ends of the jacket. However, with an interlocking arrangement as herein described, air attempting to escape would have to pass completely around the rubber-like material within the groove 19, thence completely around the web 23 and the radial flange 24, and thence around the rubber-like material within the groove 20.

There are several features about the described interlocking arrangement which operate to prevent such escape of fluid under pressure. For example, the molding of the jacket 15 to the remainder of the waveguide causes the rubber-like material of the jacket to extend within the inner groove 19 and in the space between the web 23 and the core 11 and causes those spaces to be completely filled with the rubber-like material to thereby oppose the escape of air therethrough. In addition, if air should find its way to a point between the interlocking portion 18 and the convolutions of the metal core 11 underlying that interlocking portion, the air pressure at that point would deform the rubber-like material outwardly, thus urging it very tightly into the groove 19 and into an enhanced sealing engagement with the outer surface of the web 23, so that the pressure of the air itself aids in preventing the escape of the air at the end of the jacket.

Aside from the effect of air pressure as just described for preventing the escape of air, it is obvious that for air to escape at the end of the jacket, it must pursue a circuitous and lengthy path, and this in itself presents very substantial opposition to its possible escape.

The embodiment of this invention shown in Fig. 4 differs from that illustrated in Figs. 1-3, inclusive, only in the addition of a sheath 25 of braided metal wire or braided thin metal strip material which preferably is braided upon and extends entirely about the metal core 11. The metal of which this sheath is formed preferably is somewhat flexible and of sufficient tensile strength to permit flexing of the core 11 while nevertheless preventing any material outward bulging thereof in the presence of fluid pressure therewithin. The soldering at 14, to fix the connection element 13 upon the core, permeates the

braided sheath in the vicinity of the said element so that the solder, in addition to serving as a means of affixing the flange to the core, also serves, as in the first described embodiment, to prevent the escape of fluid pressure between the element 13 and the core 11. In the structure illustrated in Fig. 4, the interlocking portion 18 functions similarly to its counterpart, as previously described with reference to Figs. 1-3.

The structure illustrated in Fig. 5 differs from that illustrated in Figs. 1-3 only in that its connection element, instead of having both inner and outer grooves such as grooves 19 and 20 of Fig. 1, is provided with only an outer groove 20a. In this arrangement, the soldering at 14 prevents the escape of fluid pressure between the connecting flange 13a and the metal core 11, and fluid pressure attempting to escape at the end of the jacket 15 would have to find its way around the radial flange 24 and thence around the rubber-like material of the jacket which fills the outer groove 20a. However, if air pressure should find its way around the radial flange 24 and to the inner radial face of said flange, the pressure of the air at that point would tend to urge the rubber-like material in the groove 20a leftwardly as viewed in Fig. 5, thereby enhancing its sealing contact with the left radial surface which defines the said groove; thus in this structure, as in that of Figs. 1-4, the air pressure itself aids in sealing against its escape.

The structure illustrated in Fig. 6 is similar to that illustrated in Fig. 5, except that it includes also a braided metal sheath 25. This sheath is like its counterpart in the structure in Fig. 4, and functions similarly thereto, and the connecting flange 13a is similar to and functions similarly to its counterpart illustrated in Fig. 5.

It should be apparent from the foregoing that by providing connection element or flange structures and a fluid-tight rubber-like jacket having its end portions interlocked with such elements or flanges according to this invention, a very effective means is provided for preventing the escape of fluid pressure from a flexible waveguide; and that flexible waveguides according to this invention may be pressurized to contain fluid pressures substantially above atmospheric pressure and thereby be rendered more efficient for the conduction of micro-wave energy. It should also be apparent that the provision of the braided metal sheath, as hereinbefore described, affords suitable means for preventing any material radial distortion of the flexible metal core which might undesirably alter the conduction characteristics of the waveguide.

Although the capacity of the herein disclosed waveguides to contain fluid pressure is limited to pressures which are not sufficiently high to cause ballooning or bursting of the rubber-like jacket, it should nevertheless be obvious that waveguides according to this invention may be adapted for containing higher fluid pressures by the simple expedient of providing a jacket which is sufficiently stronger to enable it to withstand the higher pressures.

It should be understood that the present inventive concept may be embodied in various structures other than those hereinbefore described and illustrated in the accompanying drawings, without, however, departing from the invention as set forth in the following claims.

What I claim is:

1. A flexible waveguide comprising an approximately rectangular, flexible, tubular, conductive inner core which is substantially resistant to the passage of fluid from the interior to the exterior thereof; a connection element fluid-tightly fixed to said core toward one end thereof and having an approximately rectangular inner-end portion with a substantially continuous, peripherally extending, radially opening groove therein having approximately parallel sidewalls; and a flexible, fluid impervious, tubular jacket, which is approximately rectangular throughout its length, surrounding said core and extending into lapping relationship relatively to said inner-end portion of the connection element with the material of said jacket extending into and substantially filling said groove to oppose passage of fluid between the connection element and the jacket; the jacket material in and bordering said groove being in substantially non-flexed condition, whereby such material in said groove is free of any flexing influence from such bordering material tending to loosen the said material from its filling position in the groove, said connection element further having a second such groove with the jacket material extending

thereinto and filling it, one of said grooves opening radially outwardly and the other of said grooves opening radially inwardly.

2. A flexible waveguide comprising an approximately rectangular, flexible, tubular, conductive inner core which is substantially resistant to the passage of fluid from the interior to the exterior thereof; a connection element fluid-tightly fixed to said core toward one end thereof and having an approximately rectangular inner-end portion with a substantially continuous, peripherally extending, radially opening groove therein having approximately parallel sidewalls; and a flexible, fluid impervious, tubular jacket, which is approximately rectangular throughout its length, surrounding said core and extending into lapping relationship relatively to said inner-end portion of the connection element with the material of said jacket extending into and substantially filling said groove to oppose passage of fluid between the connection element and the jacket; the jacket material in and bordering said groove being in substantially non-flexed condition, whereby such material in said groove is free of any flexing influence from such bordering material tending to loosen the said material from its filling position in the groove, said core further being formed with peripherally extending corrugations and the material of said jacket extending into and filling said corrugations.

3. A flexible waveguide comprising the combination of a substantially rectangular, flexible, tubular, fluid-tight metallic inner core, a metallic, rigid connection element having a longitudinal opening therethrough to receive said core, an end of said core being inserted in said opening and said core being fluid-tightly connected to said connection element, said connection element further comprising integrally an outer web extending longitudinally inwardly of said core, a web integral with said outer web and extending radially inwardly therefrom, an inner web integral with said radial web and extending therefrom longitudinally inwardly of said core and in spaced relation thereto, and a flange integral with said inner web and extending radially outwardly therefrom and terminating radially inwardly of said outer web, said webs and flange defining a radially inwardly open groove and a radially outwardly open groove, and said waveguide further comprising a flexible, fluid impervious tubular jacket molded around said core and in said grooves and filling the latter, said jacket further comprising a body portion having a wall of substantially uniform thickness and conforming in outer diameter to said outer web and being smoothly graduated therefrom into said body portion.

4. A flexible waveguide according to claim 2, further including a flexible sheath which is substantially non-expansive peripherally, intimately surrounding the said core and restraining the latter against peripheral expansion in the presence of fluid pressure therewithin.

5. A flexible waveguide according to claim 1, further characterized in that the said connection element has a body portion extending around the core toward one end thereof and an integral, peripherally continuous web, of S-shape in longitudinal section, extending longitudinally inwardly and being embedded within said jacket material with the reversely extending parts of the S defining the mentioned grooves; the said web, longitudinally inwardly of the mentioned inwardly-opening groove being of greater internal diameter than the corresponding outer diameter of the said core to provide space for accommodating the jacket material uninterruptedly from the body portion of the jacket to and into the said inwardly-opening groove, and said jacket material extending uninterruptedly from the body portion of the jacket to and into the said outwardly-opening groove.

6. A flexible waveguide according to claim 1, further including a flexible sheath of relatively high tensile strength, intimately surrounding the said core and restraining the latter against peripheral enlargement in the presence of fluid pressure therewithin.
